EGG CLEANING AND SANITIZING MACHINE

William L. Slocum and Harold L. Haggard,
Miami, Fla.

Application August 10, 1951, Serial No. 241,182

2 Claims. (Cl. 51—23)

1

This invention relates to egg cleaning and sanitizing machines and, more particularly, to improvements in methods and apparatus to effect substantial sterilization of the egg shell surface in the cleaning process.

We are aware that machines have heretofore been built for the removal of dirt from egg shell surfaces by directing thereagainst successive impacts of abrasive strips and providing a housing or chamber through which the eggs were passed for this purpose. We have found that the dirt-laden dust thus freed from the egg surfaces ultimately settles within interior recesses of the chamber and that the mechanisms therein, as well as the eggs, become coated with this residual dust despite blower means employed to evacuate the same. It is well known in the art, that eggs arriving from production centers carry an excessive amount of dirt on their shell surfaces and, further, that a potential source of bacterial and germ contamination likewise resides therein. Thus, while the surface dirt may well have left the shells, the abrasive strips having swiped them clean in transit through the cleaning chamber, the packaged eggs may ultimately arrive at distribution points or in the home with bacterial and germ infestation intact thereon from the residual dust settling on the egg surfaces in passage through the abrasive step of the process.

It is an object of the invention to provide an apparatus and method of the character and for the purposes described which will effectively remove surface dirt from eggs and substantially prevent or minimize the transmission of bacterial infestation or contamination thereby.

A further object is to provide egg cleaning and sanitizing apparatus which will be simple in operation and efficient in use.

Another object is to provide an egg cleaning and sanitizing machine which may be readily and economically manufactured and maintained in service.

Other advantages of the invention will be discernible from the detailed description thereof hereinafter set forth.

According to the invention, the apparatus comprises an elongated egg cleaning and sanitizing chamber through which the eggs are conducted and subjected to abrasive action for the removal of dirt from the shell surfaces thereof, germicidal light sources positioned in the chamber to direct radiations toward and through an air stream carrying the dirt laden dust resulting from the abrasive process whereby to sterilize the dust and thus the interior of the chamber and the eggs in

transit therethrough, and means operable to move the eggs through the chamber and induce the air stream therein, and effect its discharge therefrom.

5 The invention is embodied in egg cleaning and sanitizing apparatus exemplified in the accompanying drawings in which the views are as follows, like reference numerals designating identical parts throughout the several views:

10 Fig. 1, a side elevation of the machine;

Fig. 2, an isometric detail of the conveyor structure;

Fig. 3, a fractional sectional detail on line 3—3, of Fig. 1;

15 Fig. 4, a section in part taken on line 4—4 of Fig. 5;

Fig. 5, an elevation of the delivery end of the apparatus;

Fig. 6, a section on line 6—6 of Fig. 1;

20 Fig. 7, a section in part taken on line 7—7 of Fig. 5;

Fig. 8, a schematic diagram of the gear assembly driving the apparatus; and

Fig. 9, a schematic diagram of the power transmission driving the conveyor from the inner shaft drive of the apparatus.

As illustrated in the drawings, the apparatus includes an elongated housing forming a chamber defined by a pair of side walls 1, end walls 2, a bottom 3, and laterally arcuate top 4. Extending longitudinally through this chamber, is a belt conveyor 5, the loading end of which is passed over a tail wheel 6 mounted in a bracket 6A. At the delivery end thereof, the conveyor is passed over a head wheel 7 mounted in a bracket 7A.

30 These wheel supporting brackets project endwise of the housing from which they are spaced to provide convenient working stations at each end of the machine for the handling of the eggs conducted therethrough. The end walls 2 are apertured as at 8 (Figs. 5 and 6), forming passageways therethrough for the conveyor and providing air intake openings for a purpose to be hereinafter described.

35 40 45 50 The belt conveyor carries a plurality of upstanding partitions 9 (Fig. 2), which are spaced apart at intervals approximating the minor axis of the egg for the loose reception thereof between adjacent partitions, which may be secured at their bases to the belt fabric in any suitable manner known in the art.

Arranged along the side marginal edges of the conveyor, is a pair of laterally spaced rails 10 (Fig. 2), which extend throughout the housing

55 and may be supported therein from any suitable

framing structure (not shown). These rails have convex inner faces, against which the end portions of each egg are adapted to bear. Thus, as each egg is carried at its mid-portion by its weight upon the belt, the frictional engagement of its end portions with the rails 10 imparts a rolling motion to the egg which is thereby rotated upon its major axis, as will be seen.

The housing has mounted therein, a pair of laterally spaced abrading shafts 11 and 11A (Figs. 4 and 7), which may be journaled for rotation through the end walls 2. These shafts are each disposed at a distance above the conveyor and spaced outwardly therefrom. Arranged on the shafts, is a plurality of abrasive loops or strips shown only generally at 12 (Fig. 6), the function of which is to rotate with their supporting shafts whereby to deliver a succession of swiping impacts against the surfaces of the eggs conducted through the housing. These abrasive elements may, if desired, take the form described in U. S. Patent 1,964,295, dated June 26, 1934, or any similar construction practicable for the purpose here intended.

Motive power for the apparatus may be derived from a fractional horsepower motor 13 (Figs. 4 and 7), secured as by a bracket member 14 against the outer face of the adjacent end wall 2 at the delivery end of the machine.

The motor-shaft 15 is coupled in driving alignment with one of the abrading shafts 11 on which is fixed a driving gear 16. This gear is connected, through a pair of twin spur gears 17, with a driven gear 18 fixed upon the opposite abrading shaft 11A. The spur gears 17 idle upon a pair of corresponding stub shafts 19 which may be journaled in a plate 2A carried by the adjacent end wall 2. The abrading shafts 11 and 11A are thus operable in opposite rotational movement as illustrated by the diagram in Fig. 8, to deliver a downwardly directed abrasive impact against the surfaces of the eggs moving through the housing for the removal of surface dirt therefrom, as will be understood.

The opposite abrading shaft 11A terminates in a worm shaft 20 which drives a worm gear 21 (Figs. 4, 5, and 7). The worm gear is fixed on a shaft 22 journaled in a supporting bracket 23, and fixed on this shaft is a drive pulley 24. Through a belt 25, the drive pulley 24 motivates a driven pulley 26 which rotates a shaft 27 carried in the supporting bracket 1A. The shaft 27 rotates the head wheel 1 and thus the driving assembly herein set forth operates from a single motor to motivate both the abrading shafts 11 and 11A and the conveyor 5.

The construction thus far described is operable, as will be seen, to conduct the eggs through the housing and at the same time remove the surface dirt therefrom. This operation fills the housing with a fine dust in which is entrained whatever germ or bacteria infestation the eggs may have brought into the cleaning chamber. To assist in evacuating this dust, there is provided an air exhaust system to be presently described. The machine includes a germicidal light source, such for example as a tubular lamp 28 which is mounted in conventional socket members 29 secured against the inner faces of the end walls 2. This light source is energizable from electrical conductors (not shown) to emit radiations in the ultra-violet band of wavelengths.

That is to say, the radiations emitted fall in the range between ultra-violet and X-ray, or through the band of ultra-short waves. We pre-

fer, but are not limited to, the employment of ultra-violet waves as produced by the conventional mercury vapor lamp.

The light source 28 is preferably positioned so as to irradiate an air stream developing from the arrangement of an exhaust outlet 30 (Figs. 1 and 3), formed in the top of the housing and centrally thereof, in which is fitted a fan casing 31 having an exhaust nozzle 32. Arranged in the fan casing is a fan 33 driven by an overhead motor 34 whereby to induce the air stream entering the chamber through air inlets formed by the apertures 8 in the end walls of the housing, previously described; the fan and its drive assembly may be supported in any convenient manner (not shown) from adjacent housing structure, as by any suitable spider framing or the like.

In practice, the housing will be seen to provide an elongated chamber through which the eggs 20 are conducted to receive the impact of the abrasive elements, thereby filling the chamber with dirt- and germ-entrained dust. This dust is carried by the air stream hereinabove described to exhaust to atmosphere, but some portion of the dust tends to return to the lower region of the chamber, settling on interior mechanisms and on the eggs remaining in the housing. The germicidal light source, however, is adapted to irradiate the dust-laden stream and sterilize the same 25 whereby to render harmless any residual dust impinging upon eggs left in the housing for any purpose.

The housing may be built with a hingeable top or sides as desired to afford access to interior 30 mechanisms. Suitable supporting structure or framing, as at F, may be devised to bring the machine to a convenient working level.

Of course, the invention is susceptible to a variety of changes in design without departing from the scope of the appended claims.

We claim:

1. Egg cleaning apparatus comprising, in combination, an elongated housing forming a chamber and a belt conveyor to conduct a plurality of eggs in longitudinal passage therethrough, said conveyor including a head wheel and a shaft in driveable support thereof, a pair of rotatable abrading shafts disposed along each side and above said conveyor and abrasive elements carried by said shafts and rotatable thereby to deliver a succession of downwardly directed swiping movements against the surfaces of said eggs, a motor having the shaft thereof in driveable axial alignment with one of said abrading shafts and a driving gear fixed thereon, a driven gear fixed upon the opposite abrading shaft and a pair of twin spur gears interposed intermediate both said gears to effect simultaneous rotation of said abrading shafts in opposed rotational directions, 45 said opposite abrading shaft terminating in a worm shaft and a worm gear in mesh therewith, a stub shaft driveably supporting said worm gear and a drive pulley fixed on said stub shaft, a driven pulley fixed upon said head wheel shaft 50 and a belt operatively connecting said pulleys whereby to drive said conveyor and said abrading shafts from said motor, electrical conductor means energizing said motor.

2. The invention as defined in claim 1, and: 55 said housing having an aperture in each end adjacent the bottom thereof, each of said apertures forming a common conveyor passageway and air intake opening, a fan casing carried by said housing at the top and centrally thereof and forming a fan chamber in communication

with said housing, a fan arranged in said fan chamber and a motor to drive said fan to induce an air stream through said housing for the entrainment of dust removed from said egg surfaces, a germicidal light source positioned in said housing and relative to said fan chamber whereby to direct the radiations thereof through said air stream and means to exhaust said stream from said housing, electrical conductor means energizing said light source and said fan motor.
